UNITED STATES PATENT OFFICE.

GUSTAV FREIWALD, OF PORTLAND, OREGON.

CURTAIN-STRETCHER.

1,298,323.

Specification of Letters Patent. Patented Mar. 25, 1919.

Application filed February 26, 1918. Serial No. 219,290.

To all whom it may concern:

Be it known that I, GUSTAV FREIWALD, a citizen of the United States, residing at Portland, in the county of Multnomah 5 and State of Oregon, have invented certain new and useful Improvements in Curtain-Stretchers, of which the following is a specification.

This invention relates to curtain-stretchers 10 or frames for stretching lace curtains while drying.

The object of the invention is to provide a curtain stretcher constructed to insure correctness of stretching both in length and 15 width, and to rapidly effect both the attachment and removal of a curtain.

Another object is to construct a stretcher which when disassembled may be folded into a very small space for transportation 20 or storage.

With the foregoing and other objects in view, which will appear as the description proceeds, the invention resides in the combination and arrangement of parts and in the 25 details of construction hereinafter described and claimed, it being understood that changes in the precise embodiment of the invention herein disclosed may be made within the scope of what is claimed without 30 departing from the spirit of the invention.

In the accompanying drawings:—

Figure 1 represents a top plan view of a curtain stretcher constructed in accordance with this invention shown in open operative 35 position such as it assumes when the curtain is applied thereto, parts being broken out,

Fig. 2 is a side elevation thereof,

Fig. 3 is an end elevation thereof,

Fig. 4 is a detail enlarged end elevation,

Fig. 5 is an enlarged detail sectional view,

Fig. 6 is a similar view taken on the line

6—6 of Fig. 1, and

Fig. 7 is an enlarged detail plan view showing the joint for connecting the sections of the side rods.

In the embodiment illustrated, a plurality of folding trusses 1 are employed, three being here shown, the legs 2 and 3 of each truss being connected at their points of intersection by a sectional rod 4 which also connects the various trusses. (See Figs. 1 and 2).

The upper ends of the legs 2 and 3 of the trusses are connected by side bars 5 and 6 55 shown in the form of sectional rods, the sections of which are detachably connected and

are here shown held in operative position by wing nuts 7, similar nuts 7' being employed for holding the sections of the rod 4 in adjusted position.

An adjustable cross bar 8 is mounted to slide on the rods 5 and 6 and is recessed or slotted as shown at 9 to receive rod 5. This bar 8, together with said rods 5 and 6 is provided with a plurality of inwardly extending longitudinally spaced curtain receiving hooks 10, any desired number of which may be employed, said hooks being spaced apart usually about an inch or so, but obviously they may be arranged to engage a curtain 70 to be stretched through each of the edge scallops thereof, which are usually found on lace curtains.

A stationary end bar 11, connects the rods or side bars 5 and 6 at one end, and may 75 be secured to said rods by any suitable means. The end bar 11 is composed of hingedly connected sections 12, preferably of the same length, and which are connected at their meeting ends by the joint shown 80 at 13 in Figs. 1 and 7. In the form shown, one of the sections 12 has its inner end reduced to form a tongue 14 which is inserted between the furcations 15 of the other section and held clampingly engaged therewith by a set screw 16. The rods 5 and 6 extend through the outer ends of the sections 12 and are secured by means of pins 17 which extend through the ends of the rods 5 and 6 outside the cross bar 11.

The trusses 1, three of which are here shown, are each constructed as clearly illustrated in Fig. 3, the legs 2 and 3 intersecting each other and pivotally connected by the rod 4, the upper ends of said legs being 95 pivotally engaged with the rods 5 and 6, rod 5 being shown at one end extended through a longitudinally extending slot 18 formed in one of the sections 12 and at its other end through recess 9 in bar 8, (see Fig. 5) so 100 as to permit the legs 2 and 3 to open and close when the stretcher is to be collapsed or expanded. The lower ends of the legs 2 and 3 are provided on their upper edges with a plurality of screw eyes 19, any desired number of which may be employed, three being here shown on each leg spaced longitudinally apart and which are designed to form anchors for the adjustable connection of coiled springs 20 which are connected 110 at one end with the upper end of the legs 2 and 3 and at their lower ends with one

of the eyes 19 on the lower end of the other leg, for instance, one spring is connected at its upper end with the upper end of leg 2 and at its lower end with the lower end of leg 3 so that these springs exert their tension to yieldably hold the legs in set up position as shown in Fig. 3 and to hold the curtain carrying portion of the frame in open stretched condition.

10 A bar 21 is pivotally connected at one end with the upper end of leg 2 and is provided in its lower edge with a plurality of notches 22 which are designed to be adjustably engaged with a laterally projecting pin 23 carried by the upper end of leg 3 and which operates to hold said legs in spread open adjusted position (see Fig. 3).

In the use of this stretcher, the sections of rods 4, 5, and 6, having been assembled 20 and aligned as shown in Figs. 1 and 2, the stretcher is opened for about three-fourths of the width of the curtain to be stretched thereon, and which is obviously accomplished by opening out the trusses which are designed to support the stretcher. The length 25 of the curtain to be stretched having been ascertained, the adjustable cross bar 8 is positioned to receive the opposite ends thereof, and they are then tightened in this position 30 by means of the set screws or wing nuts 24 as shown clearly in Fig. 5. The stretcher is then ready to receive the curtain, the ends of which are engaged with the hooks 10 carried by the cross bars 8 and 11. After the 35 curtain has been engaged at its opposite ends with the cross bars 8 and 11, the stretcher is opened out and the side edges engaged with the hooks 10 carried by the side bars 5 and 6. After so attaching the 40 curtain the stretcher is opened to its full extent, the bar 21 being engaged with the pin 23 to hold the legs of the trusses in open relation. The springs 20 are then engaged in any one of the eyes 19 found desirable to 45 put the proper tension on the curtain to be stretched, it being obvious that these springs are adjustable and can be loosened or tightened to suit the operator.

When the curtain is dried, and it is desired to remove it from the frame, all that is necessary is to unhook the springs from the eyes 19, fold the cross bars 11 and the truss legs to cause a slack in the curtain so that it may be readily detached from the 55 hooks 10. After the curtain is removed, the stretcher is ready for the application of another curtain which may be put in place in the manner above described, the springs connected up and the bars 21 fastened and the 60 operation again repeated.

From the above description it will be obvious that a curtain stretched on this frame

will be uniform in both width and length, and while the device may be slightly more complicated than some others in use, the 65 convenience afforded and the correctness of stretching in length and width will more than compensate for the additional expense of manufacture.

When the stretcher is not in use it may 70 be folded into a very small space by collapsing the sections of rods 5 and 6 in an obvious manner.

From the foregoing description, taken in connection with the accompanying drawings, 75 the advantages of the construction and of the method of operation will be readily apparent to those skilled in the art to which the invention appertains and while I have described the principle of operation of the 80 invention together with the device which I now consider to be the best embodiment thereof, I desire to have it understood that the device shown is merely illustrative and that such changes may be made as are within 85 the scope of the claimed invention.

I claim:

1. In a curtain stretcher, a plurality of 90 folding trusses, side bars connecting the upper ends of said trusses and provided with curtain engaging means, said trusses being expandable and contractible to vary the height of the stretcher, a locking bar pivotally connected at one end to one leg of one of said trusses, the other leg of said truss and said bar having co-operating interlocking means for holding the truss in adjusted position.

2. In a curtain stretcher, a plurality of 100 folding trusses, side bars connecting the upper ends of said trusses and provided with curtain engaging means, said trusses being expandable and contractible to vary the height of the stretcher, and resilient means 105 for holding said trusses in expanded position.

3. In a curtain stretcher, a plurality of 110 folding trusses, side bars connecting the upper ends of said trusses and provided with curtain engaging means, said trusses being expandable and contractible to vary the height of the stretcher, coiled springs connected at one end to the upper ends of the legs of the trusses at one side and at their other ends to the lower ends of the other legs, one spring connecting the upper end of one truss leg and the lower end of the other.

In testimony whereof I affix my signature in presence of two witnesses:

GUSTAV FREIWALD.
